CLAIM

We claim The ornamental design for a planting system, as shown and described.

DESCRIPTION

FIG. 1 depicts a perspective view of a planting system.

FIG. 2 is a front elevational view thereof.

FIG. 3 is a rear elevational view thereof.

FIG. 4 is a side elevational view thereof.

FIG. 5 is an opposite side elevational view thereof.

FIG. 6 is a top plan view thereof.

FIG. 7 is a bottom plan view thereof; and,

FIG. 8 depicts a perspective view of a planting system depicting a layer of the top cover pulled back.

The broken lines in the drawings illustrate environmental structure on the article and form no part of the claimed design.
